Ethan H. Nichols & Thaddeus Fairbanks. of Brattleboro

Letter Patent

The Schedule referred to in these Letters Patent and making part of the same containing a description in the words of the said Ethan H. Nichols and Thaddeus Fairbanks themselves of their improvement being a Stamp and Flax Dresper.

To all persons to whom these presents shall come.

Ethan H. Nichols, of Brattleboro and Thaddeus Fairbanks of St. Johnsbury, in the County of Caledonia & State of Vermont, doth Brete.

Be it known that the said Thaddeus Fairbanks and Ethan H. Nichols have invented, constructed, made and applied to use a new and useful improvement for a Stamp and Flax dresper, designed to be applied to any or all such Stamp and Flax Machines as are constructed with rotating bristle rollers. The following is a full and exact description of the construction and operation of said improvement as invention is made by us. 1st A wooden Roll corresponding in length to the bristle Rollers of the Stamp and Flax Machine to which it is applied, this which is driven in iron shaft, which serves for guides. 2nd Iron blades or wings extending the whole length of the roll, and being riveted laterally, are made square from the surface of the roll and about 2 inches apart. These blades may be confined in parallel grooves if made of cast iron they may be double and confined by screws or bolts. These edges may be straight or indented. The roll with the blades thereto affixed may be called a dresper. Two of these drespers are placed one above the other so near together as that the blades play and mesh into each other. Two cog or gear wheels upon shafts of the dresper equalize their revolutions, and motion is given them by a belt or chain which attached to one of them. The latter is a description of the Stamp and Flax machine, as constructed upon the principles of Stone and Bain and is introduced here for the purpose of ascertaining the operation of the improvement as invented by us when applied to said Stamp and Flax Machine.

A number of pairs of fluted brake rollers (or 5 inches in diameter, usually 6 or 70 pms) are placed in iron stands supported by a frame of wood. The top rollers are then weighted at each end and ride upon the bottom ones, and the pms, lie close by side so closely as to receive the flax or hemp from one pair to another until it passes this the whole range upon each side of the machine extending the whole length is an iron shaft supported upon the wooden frame aforesaid. Small bevel wheels attached to these shafts connect at right angles with wheels upon the ends of the bottom rollers and the whole is propelled by a power at the tail of the machine. The rollers lie in a horizontal direction, the whole range forming a level flat surface and the flax or hemp is conducted into the machine by a running apron upon which it is spread and is received upon another apron at the foot of the machine.

In applying an improvement to Hines and Barry machine as directed above on pair of drapers are placed at the foot of the machine between the last pair of fluted brake rollers & the rollers connected with the pms, and are turned in the same direction as the fluted brake rollers, but with far greater velocity. one or more pairs of drapers may also be inserted at convenient distances in different parts of the machine & should the turn of the drapers exceed that of the brake rollers the relative motion should be such as to drag with the collateral brake rollers the hemp or flax fibres from the brake rollers between the drapers and is received by the next pair of brake rollers or by the rollers connected with the pms at the foot of the machine and as the progress of the hemp this the machine is gradually the action of the drapers operates to dislodge the fibres while the brake rollers are steadily proceeding down the double purpose of breaking the stem and of holding the fibre during the operation of the draper. - In testimony that that the above is a true specification of the construction and operation of the said improvement we have hereunto set our hands and seals this 6th day of September in the year of our Lord one thousand eight hundred and thirty -
